UNITED STATES PATENT OFFICE.

ADAM TYSKIEWICZ, OF ROTHSCHILD, WISCONSIN.

CONCRETE MOLD.

Application filed August 1, 1922. Serial No. 578,916.

To all whom it may concern:

Be it known that I, ADAM TYSKIEWICZ, a citizen of the United States of America, residing at Rothschild, in the county of Marathon and State of Wisconsin, have invented certain new and useful Improvements in Concrete Molds, of which the following is a specification.

This invention relates to certain new and useful improvements in concrete molds and has particular reference to that type of mold formed of collapsible sections for molding floors, walls or the like wherein reinforcing elements, such as I-beams are imbedded in the concrete.

The primary object of the invention resides in the provision of a concrete mold wherein reinforcing I-beam sections are rigidly supported in spaced relation with arch forms interposed between said I-beam for molding a reinforced floor or the like.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a fragmentary cross sectional view of a molded floor section showing the mold clamping blocks engaging the reinforcing I-beam, the intermediately positioned arch members or forms and the concrete body supported in the mold.

Figure 2 is a horizontal sectional view taken on line II—II of Fig. 1 showing the clamping blocks of the mold.

Figure 3 is a vertical cross sectional view taken on line III—III of Fig. 1 showing a part of the arch form supporting the concrete filling with the arch form supported on the clamping blocks, and

Figure 4 is a top plan view of a pair of clamping blocks shown in their separated extended position with a reinforcing I-beam positioned thereon and illustrated by dotted lines.

The present invention being especially designed for molding flat bodies or plain surfaces, such as floors, walls or ceilings of concrete having reinforcing elements imbedded therein, such as I-beams, the device embodies in detail, a plurality of clamping blocks ar-

ranged in pairs, each pair including a substantially rectangular block portion 1 having adjacent sides thereof cut away as at 2 to form overlapping leg members 3 and 4. 60 The connection between the clamping block members 1 embodies the provision of spaced horizontally alined slotted openings 5 in the block leg 4, while the leg 3 is provided with circular openings 6 registering with said 65 slots, and through which slots and openings, connecting bolts 7 extend that support nuts 8 upon the threaded ends thereof for securely holding the clamping blocks in their closed operative position. An inwardly directed upstanding clamping lug 9 is carried by the outer end of each clamping block 1 for engagement with the adjacent edges of the lower flanges of reinforcing I-beams imbedded in the concrete. 75

In the molding of a wall or similar body, a plurality of pairs of clamping blocks 1 are arranged in spaced rows and in spaced relation, the clamping blocks being separated to assume the position illustrated in Fig. 4. 80 Reinforcing I-beams 10 have the lower flanges 11 contacting the legs 3 and 4 of the clamping blocks and said blocks are moved toward each other to assume the position shown in Fig. 2, permitted by the bolt and 85 slot connection between the clamping blocks and so retained by the bolt and nuts 7 and 8. Arched forms 12 of the desired configuration, preferably of substantially U-shaped in cross section having side legs 13 90 are supported at their lower ends on the adjacent edges of the spaced rows of clamps, the side walls 13 of the arched form being cut away as at 14 to provide clearances for the clamping lugs 9 as clearly shown in Figs. 95 1 and 3. Concrete or other material 15 is then poured into the molds, covering the arched forms 12 with the I-beams 10 imbedded therein. With the clamping blocks so positioned, binding screws 16 passing upwardly through the clamping blocks engage the lower faces of the flanges 11 of the I-beams for securely clamping the same in the blocks 1. After the concrete has set and hardened, the clamping blocks 1 are separated to the position shown in Fig. 4 to disengage the clamping lugs 9 from the lower flanges 11 of the I-beam, at which time such clamping blocks may be readily removed from engagement therewith. The arched 100 forms 12 are then removed from the concrete body 15 in any desired manner leaving

105 110

the molded concrete 15 with the reinforcing I-beams 10 imbedded therein. It will be noted that the clamping blocks 1 directly engage the reinforcing I-beams 10 and the 5 arched forms 12 in setting up the molds for receiving the concrete filling 15 and said clamping blocks and arched forms are removed from the concrete body after the same has been allowed to set and harden.

10 While there is herein shown and described the preferred embodiment of the present invention, it is nevertheless to be understood that minor changes may be made therein without departing from the spirit and scope 15 of the invention as claimed.

What I claim as new is:—

1. In a concrete mold, a plurality of clamping blocks arranged in spaced relation and in spaced rows, each clamping block including separable members, means carried

thereby for engaging the adjacent side edges of the flanges of reinforcing I-beams, arch forms of inverted substantial U-shape having the opposite edges thereof supported on the opposed edges of adjacent rows of 25 clamping blocks, and binding members carried by the clamping blocks for engaging the lower faces of the reinforcing I-beam.

2. In a concrete mold, a plurality of clamping blocks arranged in spaced relation 30 and in spaced rows, each clamping block including a body portion having opposed cut away faces to form overlapping leg members, bolt and slot connections between said leg members to permit relative sliding movement thereof, and an inwardly directed clamping lug hook carried by the outer end 35 of each member of the clamping block.

In testimony whereof I affix my signature.

ADAM TYSKIEWICZ.
